UNITED STATES PATENT OFFICE.

EDWARD KNAUSS, OF FLORIN, CALIFORNIA, AND HERMAN G. ADLER, OF BROOKLYN, NEW YORK, ASSIGNEES TO K. P. PRODUCTS CO. INC., OF NEW YORK, N. Y., A CORPORATION OF NEW YORK.

GOVERNOR FOR INTERNAL-COMBUSTION ENGINES.

Application filed September 1, 1926. Serial No. 133,046.

This invention relates to governors for internal combustion engines adapted to cause the engine to maintain a nearly constant speed irrespective of whether it carries full load, no load or any intermediate load.

A distinctive feature of the invention resides in the provision of a governor or speed controller that may be adjusted to 10 operate at a wide range of engine speeds without requiring any alteration or change in any of its component parts. In that connection the invention contemplates a construction which is adaptable to different engines which have varying vacuum characteristics.

A further object of the invention is to provide a vacuum responsive element, a governing valve and mechanism for causing 20 the vacuum responsive member to move the governing valve toward its closed position at a constantly decreasing rate as compared with the movement of said vacuum responsive element which tends to straighten out 25 the curve representing the vacuum acting on the vacuum responsive element.

A further object is to employ an unbalanced governing valve subject to the differential in pressure in the mixture supply 30 duct on opposite sides thereof which causes such valve to increasingly resist the effort of the vacuum responsive element to move it toward its closed position. As the differential pressure acting on the vacuum responsive element and differential pressure acting on the unbalanced governing valve 35 to resist its closing movement depend upon the position of this valve, it is clear that when the governor is adjusted to different 40 maximum speeds a similar change will be produced in the characteristics of the differential pressures acting upon the vacuum responsive element and upon the governing valve respectively and that the difference 45 between the differential pressures acting upon the vacuum responsive element and the governing valve will remain substantially unchanged and capable under all throttle and load conditions of being balanced by 50 adjustment of the tension of the same springs without any change being required in the characteristics of such springs.

The unbalancing of the governing valve should be such that the resistance to the

movement of the piston by the unbalanced valve will not be sufficient to entirely balance the effort of the differential between the pressure in the vacuum duct and atmospheric pressure acting upon the piston, the complete balance being effected by appropriate additional spring resistance. 55

It is also apparent that this construction not only will prevent stealing or overrunning the motor speed for which the governor has been set but will, in a sense, anticipate 60 stealing and render it necessary to maintain the manually operated throttle in such open position that when the motor is running under a light load the clearance in the duct around the manually operated throttle valve 70 will be greater than the clearance in said duct around said governing valve in order to maintain such a differential between the pressure on opposite sides thereof as will prevent the complete closing of such valve. 75

A further object is to provide mechanism whereby a spring resisting the movement of the vacuum responsive element will be deflected at a disproportionately increasing rate as the vacuum responsive element moves 80 the governing valve toward its closed position and to provide means whereby the rate at which such spring is deflected as compared with the movement of the vacuum responsive element may be varied. 85

With the above and other objects in view which will more readily appear as the nature of the invention is better understood, the same consists in the novel construction, combination and arrangement of parts hereinafter more fully described, illustrated and claimed. 90

A preferred and practical embodiment of the invention is shown in the accompanying drawings, in which:

Figure 1 is a vertical longitudinal sectional view illustrating the application of the invention and showing the governing valve in its full open position.

Figure 2 is a top plan view of the device. 100

Figure 3 is a view similar to Figure 1 illustrating the relative position of the various parts of the device when the governing valve has been moved fully to its closed position.

Figure 4 is a detail and elevation of the device.

Figure 5 is a diagrammatic view illustrat-

ing the degree of piston movement with relation to the various governing valve positions to control the percentage of open area in the intake duct.

5 Figure 6 is a detail sectional view taken on the line 6—6 of Figure 2.

Figure 7 is a graph illustrating the relation of vacuum to uniform restriction of the mixture supply duct on the same engine at 10 different speeds.

Figure 8 is a graph illustrating the relation of vacuum to uniform restriction of the mixture supply duct on different engines at same speed.

15 Figure 9 is a graph illustrating the effect of our lever and valve arrangement upon the relation of open area to piston movement.

Figure 10 is a graph illustrating the vacuum equivalents of the opposing forces acting upon the piston and valve respectively and the resultant net force exerted by the piston.

Similar reference characters designate 25 corresponding parts throughout the several figures of the drawings.

According to the embodiment of the invention shown in the accompanying drawings it is proposed to provide a governing 30 valve A which is separate from but controlled by a vacuum responsive element B through the medium of a spring controlled lever device C. This device is capable of adjustment to readily adapt the device to 35 operate under different conditions on the same engine or on different engines. The vacuum responsive element B is preferably in the form of a piston which is actuated by the differential pressure occurring in the 40 intake duct down stream from the governing valve and the atmosphere so that the governing device may be made accurately responsive to changing conditions of speed and load.

45 Referring now more in detail to the construction shown in the accompanying drawings it will be observed that the same comprises a main casing or housing 1 carrying therewith an offset attaching portion 2 adapted to be interposed in the intake duct of the engine between the carburetor 3 and the manifold pipe 4 and having a valve chamber 5 which communicates through the port 6 with the mechanism chamber 7 of the main casing or housing 1. As will be 50 observed from Figure 2 the said mechanism chamber 7 is accessible through the cover plate or door 8.

Arranged within the valve chamber 5 is 55 the governing valve A which is carried by a shaft extending across the chamber 5 and journaled as at 9 and 10 in the opposite walls of the chamber. This shaft carries therewith a lever 11 having at its free end 60 a roller 12 adapted to bear against the end

13 of the hollow piston 14, of the vacuum responsive element B, slidably mounted in the tubular part of the main casing 1.

The lever 11 carries therewith a spring pilot 15 which cooperates with a pilot 16 carried by an adjusting device designated generally as D, thereby to support a spring 17 whose degree of compression may be adjusted to vary the resistance offered by the roller to the movement of the piston 14.

The adjusting device D includes the shank 18 of the pilot 16 and an adjusting screw 19 which has a threaded engagement in the adjustable sleeve 20 mounted in the slot 21 in one of the walls of the mechanism chamber 7, the longitudinal axis of the slot being at right angles to the pivot axis of the spring pilot 16 so that the lateral adjustment of said pilot may be made parallel to the path of movement of the roller 12 across the face or end 13 of the piston 14. The inner end of the sleeve 20 is provided with the elongated rectangular guiding portion or head 22 adapted to have a guiding engagement with a side of the mechanism chamber 7 to prevent the twisting of the sleeve when it is adjusted. It will also be observed that the shank 18 of the spring pilot 16 is provided with a groove 18^a adapted to receive a key 18^b to prevent the rotation of the said shank when the same is moved by the adjusting screw 19. It will therefore be apparent that the shank 18 of the pilot and the screw 19 are separate members, the screw 19 being held in the desired set position by the nut 19^a. Also to hold the sleeve 20 at the proper setting the same is provided with a nut 20^a bearing against the outer face of the chamber 7 and partially covering the slot 21. In order that air pressure will not enter the chamber 7 through the slot 21 a gasket 22^a is clamped between the head 22 and wall of chamber 7. A hood 23, as clearly shown in the drawings, is provided to prevent tampering with the parts when adjusted.

With the foregoing arrangement it will be apparent that the pilot 16 of the spring 17 has two adjustments, one effected by the screw 19 for varying the tension of the spring 17, and the other effected by the sleeve 20 for changing the relative position of the pilot in the chamber 7 to shift the longitudinal axis of the spring toward and from the shaft 9 carrying the valve.

As previously explained the roller 12 bears against the face 13 of the piston 14 of the vacuum responsive element so that as the said piston moves in the main casing or housing 1 the roller is shifted across the end of the piston as indicated in Figure 5. The various positions of the roller due to piston movement, and the positions of the valve are clearly plotted out in the diagram referred to and also the percentage of open

area in the intake duct is graphically illustrated for each position of the piston and the valve. From the diagram it will be observed that the initial movement of the piston 5 will cause the valve to cut off or close a greater area of the intake duct than a like subsequent movement thereof and that each subsequent like movement of the piston will cause the valve to cut off or close a progressively decreasing area of the intake duct. It is also apparent that on the contrary a given initial movement of the piston will cause but a slight deflection of the spring 17 and that each like subsequent movement 10 of the piston will cause a progressively increasing deflection of said spring.

The hollow piston 14 is maintained in its normally retracted position by the spring 17. The spring 24 is secured at one end in grooves 20 in an adjustable pin or support 25 which is adjustably fitted in the cover or plug 26 inserted in one end of the main casing 1. The free end of the spring 24 is adapted to be engaged by a washer or equivalent abutment 25 carried by the piston 14, the said washer having a central opening to clear the member 25 and avoid frictional resistance at that point. The cover or plug 26 is provided with openings 28 to permit atmospheric pressure 25 to exert its influence on the side of the piston opposite the roller 12. Also as shown the cover plug 26 may be provided with a guard or cap 29 having an atmosphere port 30 to insure communication to the piston 35 through the openings 28. Although a single spring 24 is shown in the drawings it will of course be understood that one or more springs may be employed if desired, and by reason of the adjustable mounting of the pin 40 or support 25 in the plug 26 it will be apparent that the same may be adjusted longitudinally along the axis of the plug to space the washer 27 from the end of the spring 25 any desired distance so that the initial movement 45 of the piston will not be resisted by the spring 24, but only by the spring 17 thereby to give the quick initial movement to the vacuum responsive element. It is also apparent that the characteristics of this spring 50 may be adjusted by changing the number of action coils by rotating it in the spiral grooves in the member 25. It will be apparent that it is possible to effect an adjustment of the governor to suit widely varying 55 conditions. Thus, the invention attains its object to provide a speed controller which can be adjusted to operate at any speed without requiring a change in any of its component parts and which may be adjusted to 60 different motors having variant or changing vacuum characteristics.

By reference to Figure 7, it will be observed that curve #1 shows the manner in which the difference in pressure between the 65 atmosphere and the vacuum existing in the

manifold varies when the open area of the fuel passage is closed at a uniform rate, and the load is adjusted to maintain a constant speed. Curve #2 shows the same relation at a lower speed, and curve #3 at a still lower speed. It will be noted that the shape of these curves is different at different speeds and that the lower the speed, the greater the bending of the curve, so that as the speed decreases, the slope of the lower portion of the curve decreases while the slope of the upper portion increases.

Curves #1 and #2 of Figure 8 show the change in vacuum which takes place at the same speed but on different engines, that is 70 when the same fuel passage is closed as described on engines of about the same size but different make and having variant vacuum characteristics, at the same speed. It will be noted that both the shape of the curve and the magnitude of the vacuum are slightly 75 different on different engines.

Accordingly, it will be apparent, that the same device will not operate with the same efficiency on different engines, or at different speeds on the same engine without a change in some of its component parts. Heretofore it has been necessary to employ different springs to balance the acting force at different speed settings and with motors of variant vacuum characteristics or to vary the acting force. However, with the present construction by utilizing a vacuum function of the engine to oppose the closing movement of the governing valve, it is possible to apply 90 the device to different motors and adjust the same to the point of efficient operation at widely variant engine speeds without changing any of its component parts.

When the device is in operation, the vacuum existing in the manifold 4 down stream of the governing valve A will also exist in the mechanism chamber 7 since the latter communicates with the fuel passage or valve chamber 5 through the opening 6. Atmospheric pressure admitted through the holes 28 will act upon the rear of the piston 14, and since the pressure on the up stream side of the governing valve A will be greater than the pressure on the down stream side, a 105 torque will be imposed upon the governing valve because of the fact that it is offset, that is the center line of the axis 9 of the valve A is displaced a certain distance from the geometrical center of the fuel passage or valve chamber 5. The torque thus imposed on the valve will act in opposition to the force acting upon the piston and the characteristics of the torque will depend upon the vacuum 110 and hence the speed. The result of the push on the piston and the opposing force due to the valve, will be a curve whose shape will be approximately the same at a large range of speeds.

Curve #1 of Figure 7 illustrates the rela- 115

tion of piston movement and open area of fuel passage. It will be observed that due to the arrangement of the lever 11 and offset governing valve shown in the drawing, this area decreases more rapidly at the beginning of the closing movement which straightens the vacuum curve as shown in Figure 10 wherein curve #1 is a vacuum curve obtained by an element which uniformly closes the fuel duct and curve #2 represents the relation of piston movement and vacuum resulting from the arrangement shown on the drawing. Curve #3 of Figure 10 represents the vacuum equivalent of the opposing force acting on the piston due to torque on the valve, and curve #4 is the resultant of this force and curve #2 or the net force on the piston. This curve is balanced by the springs 17 and 24. As previously set forth the spring 24 may consist of one or more springs arranged in series or parallel, so that a certain portion of the force represented by the ordinate of curve #4 is balanced by it. By reason of the adjustable mounting for the spring 17 it will be apparent that as the roller 12 moves to close the governing valve, the force inherent in this spring will first increase slowly and then more rapidly, thus forming a smooth curve, the shape of which will depend upon the initial tension and characteristics of the spring 17, as well as upon the position of the adjusting screw 19. By moving the sleeve 20 toward the manifold 4 the bending in the curve of the spring 17 will be decreased, and vice versa. The resultant vacuum can therefore be completely balanced by the springs 17 and 24 on any motor at any speed.

Without further description it is thought that the features and advantages of the invention will be readily apparent to those skilled in the art, and it will of course be understood that changes in the form, proportion and details of construction may be resorted to, without departing from the spirit of the invention or scope of the appended claims.

We claim:

1. A governor for internal combustion engines including an unbalanced governing valve, and vacuum responsive means for moving said governing valve toward its closed position.

2. A governor for internal combustion engines including a mixture supply duct, an unbalanced governing valve mounted therein, vacuum responsive means for moving said unbalanced governing valve toward its closed position, said unbalanced governing valve constituting flow actuated means for opposing its closing movement.

3. A governor for internal combustion engines including a mixture supply duct, an unbalanced governing valve mounted therein, vacuum responsive means for moving said

unbalanced governing valve toward its closed position, said unbalanced governing valve constituting flow actuated means for opposing its closing movement and spring means for balancing the resultant net force of said vacuum and flow responsive means.

4. A governor for internal combustion engines including a mixture supply duct, an unbalanced governing valve mounted therein, means actuated by the differential between the pressure in said duct down stream from said governing valve and atmospheric pressure for moving said governing valve toward its closed position at a gradually decreasing speed as compared with the movement of said vacuum responsive element, the said unbalanced governing valve being so mounted in said mixture supply duct that the flow effect on said unbalanced governing valve will energize said governing valve to exert a disproportionately progressively increasing resistance to the closing effort of said vacuum responsive element as it is moved toward its closed position.

5. A governor for internal combustion engines including a vacuum responsive element, a governing valve, separate spring resistance means respectively for said valve and vacuum responsive element, and means for separately adjusting said spring resistance means to balance the vacuum curve at any engine speed.

6. A governor for internal combustion engines including a vacuum responsive element, a governing valve, adjustable spring resistance means for the vacuum responsive element, separate spring resistance means for the valve, and means for adjusting said last named spring resistance means to vary the force thereof and the direction of application of said force.

7. A governor for internal combustion engines including a governing valve, a vacuum responsive element adapted to be subjected to pressure conditions in the intake duct down stream from said governing valve, spring resistance means for said vacuum responsive element, and separate spring resistance means for the governing valve adapted to be adjusted to offer varying resistance to the vacuum responsive element to balance the vacuum curve at any engine speed.

8. A governor for internal combustion engines comprising a vacuum responsive element including a piston adapted to be subjected to vacuum conditions in the intake duct of the engine and atmospheric pressure, a governing valve in the intake duct, an actuator for the governing valve including a lever adapted to be moved by the said piston, spring resistance means for said lever, and means for shifting the position of and adjusting the said spring resistance means.

9. A governor for internal combustion engines comprising a vacuum responsive element including a piston, a pivoted governing valve arranged in the intake duct of the engine, and means for operating said valve, said means comprising a lever adapted to be moved by the piston, a spring connected to the free end of said lever, and means for compressing said spring and shifting the end thereof opposite the lever toward and from the longitudinal axis of the piston.
10. A governor for internal combustion engines comprising a vacuum responsive element including a piston, a pivoted governing valve arranged in the intake duct of the engine, and means for operating said valve, said means comprising a lever, a spring for maintaining the end of said lever in operative relation to the end of the piston, and means for adjustably mounting said spring including a spring support adjustable parallel to the longitudinal axis of the piston and a carrier for said spring support adjustable at right angles to the longitudinal axis of the piston.
11. A governor for internal combustion engines comprising a vacuum responsive element including a piston adapted to be subjected to vacuum conditions in the intake duct and atmospheric pressure, adjustable spring resistance means for the piston, a governing valve arranged in the intake duct of the engine, and means for controlling the movement of said valve, said means comprising a lever adapted to be moved by the piston, a spring connected with the free end of said lever and normally thrusting the same toward the piston, and means associated with the end of said spring opposite the lever for shifting the same and varying the compression thereof.
12. A governor for internal combustion engines comprising a pivoted governing valve arranged in the intake duct of the engine, a vacuum responsive element including a piston adapted to be subjected to vacuum conditions down stream from the governing valve and atmospheric pressure, adjustable spring resistance means for the piston, and means for operating said governing valve upon movement of the piston, said means comprising a lever, a roller on said lever adapted to travel across one end of the piston, and spring resistance means for maintaining said roller in contact with the piston.
13. A governor for internal combustion engines including a main casing having a mechanism chamber and an offset valve chamber communicating therewith and adapted to be arranged in the intake duct of the engine, a piston slidably mounted in the main casing, a governing valve pivotally supported in the valve chamber and having the pivot portion thereof extending into the mechanism chamber, a lever for the valve, a spring for maintaining said lever in operative relation to the piston, and means for adjusting said spring comprising a support adjustable parallel to the axis of the piston to vary the compression of said spring, and a sleeve carrying said support and adapted to be adjusted toward and from the longitudinal axis of the piston.
14. A governor for internal combustion engines including a vacuum responsive element, spring means associated with said element, a governing valve carrying an actuator operatively engaged with the vacuum responsive element and spring means maintaining said operative engagement.
15. A governor for internal combustion engines including a vacuum responsive element, adjustable spring means associated with said element, a governing valve carrying an actuator operatively engaged with the vacuum responsive element and spring means maintaining said operative engagement.
16. A governor for internal combustion engines including a vacuum responsive element, spring means associated with said element, a governing valve carrying an actuating rocker operatively engaged with the vacuum responsive element and spring means maintaining said operative engagement.
17. A governor for internal combustion engines including a governing valve, vacuum responsive means for moving said governing valve towards its closed position, a spring opposing the movement of said vacuum responsive means, and means for causing said spring to be deflected at a continuously increasing rate as compared with the movement of said vacuum responsive means.
18. A governor for internal combustion engines including a governing valve, vacuum responsive means for moving said governing valve towards its closed position, a spring opposing the movement of said vacuum responsive means, means for causing said spring to be deflected at a continuously increasing rate as compared with the movement of said vacuum responsive means and means for varying the rate at which such deflection of said spring is so increased.
